UNITED STATES PATENT OFFICE.

HARRY SEBELL, OF BOSTON, MASSACHUSETTS, ASSIGNOR TO LOUIS F. BUFF, OF BOSTON, MASSACHUSETTS.

WINDOW CATCH.

Application filed July 17, 1926. Serial No. 123,078.

The invention relates to window catches and has for its object to provide a novel window catch which can be inexpensively manufactured and which will be effective 5 in operation.

In order to give an understanding of the invention I have illustrated in the drawings a selected embodiment thereof which will now be described after which the novel features 10 will be pointed out in the appended claim.

Fig. 1 is a fragmentary perspective view showing a window catch embodying my invention;

15 Fig. 2 is a sectional view on the line 2—2, Fig. 1;

Fig. 3 is a front view of Fig. 2.

A window catch constituting my invention 20 is of that type which is adapted to be secured to the top edge of the lower sash and is adapted to lie against the side rail of the upper sash.

In the drawings 1 indicates the lower sash and 2 the upper sash of a window.

25 My improved catch comprises a housing 3 which is secured to the top edge 4 of the lower sash 5 and which carries a locking member 6 that frictionally engages the side rail 7 of the upper sash. This housing is 30 of such a shape and has such a construction that when it has been secured in place it cannot be removed except by taking out the window sashes. The housing comprises the top 8, the bottom 10 and the two side 35 walls 9 which connect the top and bottom. This housing is open at both ends. The bottom is formed with an ear 11 to receive an attaching screw 12 which is screwed into the window sash. The housing is also made 40 with a depending flange 13 which overlies the outside face 14 of the upper rail of the lower sash and which lies between said face and the side face of the upper sash.

45 A nail, screw or other fastening means 15 is inserted through the apron 13 into the upper sash. When the window sashes are in place this apron 13, which is secured to the upper sash by the fastening 15, is confined between the two sashes and thus the 50 fastening 15 cannot be removed except by taking the windows out from the window frame.

55 The latching member 6 has a cylindrical shape, the periphery of which is preferably knurled as shown at 16. This latching mem-

ber is pivotally mounted on a pivot pin 17 which is carried by the side walls 9, said pivot pin being situated eccentrically of the locking member as best seen in Fig. 2.

The latching member is acted upon by a 60 spring 18 which holds it yieldingly against the face of the side rail 7 of the upper sash. This spring is in the form of a spring wire having a U-shape, the two arms of which are wound around a pin 19 which is carried 65 by the side walls 9, the two ends 20 of the arms resting against the bottom 10 of the housing. The spring thus holds the locking member 6 yieldingly against the side rail 7 of the upper sash. The pivotal pin 17 is 70 situated below the center of the latching member so that the lower sash is free to move downwardly relative to the upper sash or the upper sash is free to move upwardly 75 relative to the lower sash. If, however, an attempt is made to move the lower sash upwardly or the upper sash downwardly the friction between the latching member 6 and the face of the sash will tend to turn the latching member counter-clockwise Fig. 2 80 thus causing the latching member to wedge against the upper sash and securing the window.

Novel means are provided for withdrawing the latching member from securing engagement with the upper sash when it is desired to open the window. The means provided for this purpose comprises a releasing member indicated generally at 21 and having a fork shape. This releasing 85 member is pivoted on the pin 19 and comprises the two arms 22 between which the latching member 6 is received. The locking member has a projection 23 extending from each end, these projections being engaged 90 by the arms 22. The two arms are connected by the bridge portion 24 and the latter has a finger piece 25 extending therefrom which is accessible through the open end of the housing.

When anybody inside of the house desires to open the window he may depress the thumb piece 25 with this finger or thumb as shown by dotted lines Fig. 2 thereby swinging the releasing member 21 about its pivot 19. During such swinging movement the engagement of the arms 22 with the projection 23 will turn the latching member about its pivot 17 into the dotted line position thus releasing it from frictional en- 100 105 110

gagement with the upper sash. The window is then free to be moved in either direction.

When the thumb piece 25 is released the spring 18 will bring the latching member 5 into securing engagement with the upper sash thus securing the lower sash from upward movement and the upper sash from downward movement.

The device is quite simple to manufacture 10 and is easily applied and is very effective in operation.

I claim:

In a window catch, the combination with 15 upper and lower sashes, of a housing resting on the top edge of the upper sash and having a depending flange confined between the sashes, a fastening means extending through said flange into the lower sash, an

eccentrically-pivoted cylindrical latching member situated within the housing, said 20 latching member having a projection extending from each end, a spring acting on said member and yieldingly holding it against the upper sash, a forked releasing member pivoted in the housing and embracing the 25 latching member, the arms of said releasing member engaging said projections, said releasing member having a thumb piece extending through the open end of the housing, whereby when the thumb piece is depressed the releasable member is rocked and the latching member released from its engagement with the upper sash.

In testimony whereof, I have signed my name to this specification.

HARRY SEBELL.
